PROCESS FOR THE PRODUCTION OF
BUTADIENE

Charles E. Ayres, Phillips, Tex., assignor to Phillips Petroleum Company, a corporation of Delaware

Application May 7, 1943, Serial No. 486,032

12 Claims. (Cl. 260—680)

This invention relates to a process for the production of butadiene. More particularly, it relates to the production of butadiene from cyclohexane by an improved process.

That butadiene may be produced from cyclohexane is known to those skilled in the art of butadiene production. It is known that butadiene may be produced in this manner by contacting the cyclohexane with a hot contact body, as aluminum silicates heated to a dark red color. Butadiene has been produced also by passage of cyclohexane through a quartz tube heated to 1200° F.

The present invention provides an improved process for producing butadiene from cyclohexane. By means of the invention, a high yield of butadiene may be obtained, the reaction is readily carried out in commercial apparatus, and the reaction may be carefully controlled. The cracking operation may be performed at optimum temperature and with optimum residence time at the cracking temperature to produce a maximum yield of the desired product.

In the pyrolytic decomposition of organic compounds it is often true that the greatest amount of the desired product is formed at higher temperatures. It is also true that at these higher temperatures the reaction time or residence time is very short, being in the order of seconds or fractions of seconds. With the conventional methods of heating a considerable interval of time is spent in raising the temperature of the compound to the desired level. During this interval of time the cracking reaction is taking place at temperatures other than the most efficient, resulting in the production of too great a volume of undesirable products. In the method set forth by this invention where the compound to be cracked is injected in a relatively small volume into a large volume of gas already heated to or above the desired temperature, the temperature of the compound to be cracked is raised almost instantaneously to the proper level enabling the reaction to take place at the temperature proper for maximum production.

An object of this invention is to provide an improved process for the production of butadiene.

A further object of this invention is to provide an improved process for cracking cyclohexane to produce butadiene.

Another object of this invention is to provide a process for simultaneous cracking of propane and cyclohexane to form valuable hydrocarbon products.

Other objects and advantages of this invention

will be apparent to those skilled in the art from a consideration of the following detailed description and the accompanying drawing.

Figure 1 is a diagrammatic elevation of an apparatus suitable for carrying out the process of the present invention.

Figure 2 is a plan view of apparatus suitable for use with the process of the invention showing a reaction zone in the form of a coil of tubing with points of entry of the various fluids.

In accordance with the present invention, the cyclohexane to be cracked is injected into a stream of fluid, inert to or beneficial to the formation of butadiene, at or near the reaction temperature. This is carried out by heating the stream of fluid to about the reaction temperature, injecting cyclohexane into the stream, maintaining the temperature for the optimum reaction time, and cooling the mixture below the reaction temperature at the end of said reaction time. In this manner it has been found possible to raise the temperature of the cyclohexane quickly from a value below the decomposition temperature to a temperature within the range at which decomposition or cracking occurs. The cyclohexane is mixed in this manner with a moving stream of the carrier fluid. By correlation of the volume of the reaction zone with the rate of flow therethrough, the reaction time may be carefully controlled. Satisfactory methods of making these correlations under the variable conditions which exist in actual operations will be made evident by the following detailed description.

With reference to Figure 1 of the drawing, the carrier fluid, propane for example, is introduced through line 5 to a heating zone 6, suitably the convection section of a petroleum cracking furnace 7 of conventional design. From the convection section, in which the propane is preheated, the propane passes to the radiant sections 8A and 8B of the furnace for cracking and then passes to the soaking coil 9 maintained at about the reaction temperature conducive to the conversion of propane and cyclohexane to the desired decomposition products.

Cyclohexane is passed through line 11 to the heating coil 12 where it is preheated to an elevated temperature somewhat below the reaction temperature. The preheated cyclohexane is carried by a conduit 13 to the valves 14A, 14B and 14C through which it may be admitted to the reaction zone, soaking coil 9, entering the zone at any of various points along its length. The cyclohexane upon mixing with the propane and

its decomposition products in the soaking coil is almost instantly heated to its decomposition temperature. The reaction time may be controlled by admission of the cyclohexane at the proper point along the soaking coil. The effluent of the reaction zone may be admixed with coolant introduced through line 15 or may be cooled by any conventional means to a temperature below the reaction temperature. The cooled effluent passes by line 16 to the separation system 17. The effluent of the cracking step will generally comprise a complex mixture of various hydrocarbons resulting from the cracking. The separation of desirable products from this mixture will depend of course upon its composition and various other factors evident to those skilled in the art. The various steps involved in the separations are more or less conventional and the selection of the proper steps becomes a matter of engineering and economics. For the purpose of this invention it is necessary only to indicate the separation system diagrammatically. For simplification, also, only the more important components of the effluent have been indicated on the drawing although any degree of separation may be made in practice. A recycle stream comprising unconverted cyclohexane is passed through line 18 to line 13 for recycling into the reaction zone. Benzene may be separated from the effluent and withdrawn from the separation zone through line 19 from which it may be passed to a hydrogenation step 20 for reconversion to cyclohexane. The cyclohexane thus formed is recycled to the reaction zone for further conversion to butadiene. The butadiene formed is withdrawn from the separation system through line 22 through which it passes to storage, further purification, or disposal. The residual hydrocarbons, i. e. the components which make up the balance of the effluent are passed through line 24 to suitable disposal means.

With reference to Figure 2 of the drawing, piping of a conventional tubestill heater is shown illustrating the points of introduction of cyclohexane to the tubing coil. The coil 25 may represent any or all of the various heating sections 6, 8A, 8B, and 9 of Figure 1. The carrier fluid, for example a fluid comprising propane is introduced to the coil 25 at the inlet 26. This fluid is heated to a temperature at or slightly above that required for the cyclohexane cracking. Fluid comprising cyclohexane is introduced at any or all of the points of injection represented by the numerals 27A, 27B, and 27C which correspond to the inlets controlled by valves 14A, 14B, and 14C, respectively, of Figure 1. The coolant, from pipe 15 of Figure 1, may be introduced to the coil at or near the furnace outlet 28 through the inlet 29.

A large volume of gas, vapor, or liquid carrier fluid is fed to the furnace coil at the inlet 26. The character of this feed stock may be inert or active; i. e., if the process is designed solely for the purpose of cracking the compound to be injected, the feed stock may be inert but, if it is desired to process the feed, some such stock as an organic compound may be used. The feed stock passes through the furnace coil and is heated to the proper reaction temperature. The cyclohexane is introduced into the furnace coil at one of the injection inlets 27A, 27B, and 27C. The desirable point of injection is determined by design and calculation and is the point where the cyclohexane will be raised almost instantaneously to the optimum reaction temperature and will re-

main at that temperature for the proper interval before cooling. The most desirable point of injection may be at inlet 27C near the furnace outlet or, if more residence time is desired may fall at inlets 27A or 27B. The ratio of carrier fluid to cyclohexane usually will be high to provide sufficient heat inertia to withstand the thermal shock of the addition of the injected cyclohexane.

Cyclohexane may be cracked or decomposed with the production of butadiene at temperatures within the range of 1100 to 1500° F.; with the present invention the higher portion of this temperature range may be most satisfactorily employed. The preferred temperatures used in the process of this invention are within the range of 1300 to 1500° F., suitably about 1400° F. Near-atmospheric or low superatmospheric pressures may be advantageously employed. Pressures of about atmospheric to about 100 pounds per square inch gage are suitable. Yields comparable to those obtained heretofore at subatmospheric pressures may be obtained by the process of the present invention at atmospheric or low superatmospheric pressures. The advantages attendant upon the use of atmospheric or higher operating pressures in contrast to operations requiring subatmospheric pressures are known to and apparent to those skilled in the art.

The preferred reaction time is within the range of about 0.1 to about 2 seconds. A reaction time of about 0.5 second has been found very satisfactory. The shorter reaction times may be used when temperatures near the upper limit of the temperature range are employed, while longer reaction times are required for optimum yields when lower temperatures are employed. By correlating the various operating conditions, butadiene yields of about 30 weight percent may be obtained from the cyclohexane cracked. The yield is increased when the benzene formed in the cracking step is hydrogenated and recycled. The total yield may be increased by about 4 to 5 weight percent by hydrogenation of the benzene to cyclohexane and recycling for further conversion.

By the present invention, cyclohexane may be cracked satisfactorily in furnace tubes of ferrous metal alloys.

While propane and its decomposition products are used throughout this specification as preferred carrier fluids, it is to be understood that the process is not limited thereby and other relatively inert or beneficial fluids may be employed. The hydrocarbons of low molecular weight are preferred, as for example paraffins and olefins of one to five carbon atoms per molecule. Thermal decomposition of the carrier fluid may advantageously take place, as in the case of propane illustrated herein, with the formation of valuable products. By this means the apparatus employed in preheating and carrying out the cyclohexane cracking serves a double purpose which is highly advantageous. A further advantage of such combination of two reactions is that the same separation equipment may be used to separate like components formed in the two reactions. For example, ethylene formed in the cracking of propane and in the cracking of cyclohexane may be removed from the effluent of the reaction zone in a single separation step.

The products of the cyclohexane cracking comprise hydrogen, methane, butadiene, and various other saturated and unsaturated hydrocarbons as will be evident from the examples.

Various amounts of carrier fluid may be used; the ratio of carrier fluid to cyclohexane may be within the range of 10 gas volumes of carrier fluid to 1 gas volume of carrier fluid for each gas volume of cyclohexane. About 4 gas volumes of carrier fluid to each gas volume of cyclohexane has been found satisfactory when using propane as the carrier fluid as indicated. The coolant used may be the same as the carrier fluid or may be any fluid inert to the products of the reaction. Cooled effluent may be advantageously employed as coolant fluid for injection at the furnace outlet or any of the components of the effluent may be advantageously employed, as for example liquid propane and butane.

EXAMPLE I

A continuous coil was immersed in a molten salt bath maintained at 1402° F. Propane was passed through the coil at a constant rate. Cyclohexane feed stock comprising about 80 weight percent cyclohexane was vaporized and injected into the propane stream at a point in the coil about two thirds of the distance from the propane inlet to the effluent outlet. The flow rates of propane and cyclohexane were so correlated with the relative volumes of the two zones in the coil as to approximate a 3 to 1 mol ratio of propane to the cyclohexane feed stock. The cyclohexane feed stock analysis was as follows:

Component	Liquid volume percent	Weight percent
n-Hexane	3.31	2.86
Me-cyclopentane	4.14	4.08
Isoheptanes	11.81	10.62
Cyclohexane	80.74	82.44

The pressure was substantially atmospheric with a residence time in the coil of 2.26 seconds for propane and 0.57 second for cyclohexane, the propane having a residence time of 1.69 seconds prior to introduction of the cyclohexane feed. The composition of the total effluent was as follows:

Component	Mol percent	Weight percent
Hydrogen	14.63	0.99
Methane	25.51	18.58
Ethylene	23.72	22.09
Ethane	3.82	3.81
Propylene	9.82	13.74
Propane	9.19	12.37
Butadiene	3.59	6.44
Butylenes	0.99	1.84
Butane	0.17	0.33
Pentadiene	0.77	1.81
Other C ₅ hydrocarbons	0.41	0.94
Cyclohexane	6.30	17.62
Unsaturated C ₆ hydrocarbons	0.72	2.00
C ₇ -C ₈ hydrocarbons	0.27	0.66
Heavier hydrocarbons	0.09	0.48

Of the butadiene formed, 1.2 weight percent is attributable to the propane. The butadiene yield from the cyclohexane feed is, therefore, 5.51 weight percent or a yield of 29.8 weight percent based on the cyclohexane cracked.

EXAMPLE II

225,000 lb./day of a propane feed stock as carrier fluid is passed through a furnace of the type shown in Figure 1 of the drawing. The total residence time of the propane and products thereof is about 2 seconds. The propane feed stock is heated to about 1400° F. at a pressure of about 15 pounds per square inch gage and a

preheated cyclohexane feed stock, at about 1200° F. injected into the carrier fluid as shown in the drawing. The cyclohexane residence time is about 0.5 second. The quantities of various hydrocarbons in the feed stocks are as follows:

Propane feed stock (carrier fluid)

Component	Lb./day
Methane	9,600
Ethane	61,800
Propane	306,500
Butane	2,600
Total	380,500

Cyclohexane feed stock

Component	Lb./day
Cyclohexane	77,600
Paraffins	18,500
Total	96,000

Unconverted cyclohexane, together with some 25 unsaturated C₆ hydrocarbons and some C₇ and heavier hydrocarbons, is recycled to the point of introduction of cyclohexane. The analysis of the recycle is as follows:

Recycle

Component	Lb./day
Unsaturated C ₆ hydrocarbons	7,200
Cyclohexane	90,000
C ₇ and heavier hydrocarbons	3,800
Total	101,000

The total effluent of the reaction zone is treated 40 for separation into various desirable fractions including a fraction comprising the butadiene produced and a fraction making up the recycle stream. The analysis of the effluent is as follows:

Effluent

Component	Lb./day
Hydrogen	5,050
Methane	73,600
Ethylene	112,100
Ethane	81,200
Propylene	70,000
Propane	68,000
Butadiene	32,800
Butenes	9,400
Butane	1,700
Pentadienes	0,200
Pentanes	4,800
Cyclohexane	90,000
Benzene	3,000
Other C ₆ hydrocarbons	7,200
Cr-C ₈ hydrocarbons	4,900
Heavier hydrocarbons	2,450
Total	580,400

About 30 weight percent conversion of cyclohexane to butadiene, based on the weight of cyclohexane cracked, is obtained. About 1,000 lb./day additional butadiene is obtained by hydrogenation of the benzene to form cyclohexane and recycling the cyclohexane so produced.

I claim:

1. A process for the production of butadiene from cyclohexane which comprises heating a hydrocarbon carrier fluid to a temperature above about 1100 but not above about 1500° F., heating cyclohexane to an elevated temperature below that of the carrier fluid, admixing the cyclo-

hexane with the carrier fluid in proportions within the range of 1 to 10 volumes of said carrier fluid per volume of cyclohexane such that the temperature of the resulting mixture is substantially instantaneously brought within the range of 1100 to 1500° F., holding the resulting mixture at a temperature within said range for a period of time within the range of 0.1 to 2 seconds sufficient to effect conversion of said cyclohexane to butadiene, cooling the resultant mixture, and separating butadiene therefrom.

2. A process for the production of butadiene from cyclohexane which comprises heating a hydrocarbon carrier fluid to a temperature above about 1300 but not above about 1500° F.; admixing cyclohexane at a temperature below its decomposition temperature with said carrier fluid at said temperature in proportions within the range of 1 to 10 volumes of said carrier fluid per volume of cyclohexane and thereby effecting substantially instantaneous heating of the cyclohexane from a temperature below its decomposition temperature to a temperature within the range of about 1300 to about 1500° F., holding the resulting mixture at a temperature within said range for a period of time within the range of about 0.1 to 2 seconds sufficient to effect conversion of said cyclohexane to butadiene, cooling the resultant mixture, and separating butadiene therefrom.

3. A process for the production of butadiene from cyclohexane which comprises passing a hydrocarbon carrier fluid through a closed elongated reaction zone formed by a heating coil at a pressure within the range of about atmospheric to about 100 pounds per square inch gage and at an elevated temperature such that the carrier fluid is brought to a temperature above about 1300 but not above about 1500° F., admixing cyclohexane with said carrier fluid by injecting same into said zone adjacent the end thereof in proportions within the range of 1 to 10 volumes of said carrier fluid per volume of cyclohexane such that the temperature of the resultant mixture is substantially instantaneously brought within the range of 1300 to 1500° F., holding the resulting mixture at a temperature within said range for a period of time within the range of about 0.1 to 2 seconds sufficient to effect conversion of said cyclohexane to butadiene, cooling the resulting effluent of said zone, and separating the butadiene therefrom.

4. A process for the production of butadiene from cyclohexane which comprises passing a hydrocarbon carrier fluid through a closed elongated reaction zone of restricted cross-section and having a fluid inlet and a fluid outlet and maintained at near-atmospheric pressure and an elevated temperature such that the temperature of said fluid is above about 1100 and not above about 1500° F., injecting along said reaction zone cyclohexane into admixture with said carrier fluid in proportions within the range of 1 to 10 volumes of said carrier fluid per volume of cyclohexane such that the temperature of the resulting mixture is substantially instantaneously brought within the range of about 1100 to about 1500° F., the cyclohexane being admixed with the carrier fluid in the zone at such a point relative to the fluid outlet thereof as to limit the residence time of the cyclohexane in said zone to a period within the range of 0.1 to 2 seconds, holding the resulting mixture at a temperature within said range for said period to effect conversion of said cyclohexane to butadiene, cooling the resulting

effluent of said zone to a temperature below that at which decomposition of cyclohexane takes place, and separating the butadiene from said effluent.

5. A process for the production of butadiene from cyclohexane which comprises passing a stream of propane into a closed elongated reaction zone of restricted cross-section at elevated temperature, heating said stream to a temperature above about 1100 but not above about 1500° F. at near-atmospheric pressure, injecting cyclohexane into said stream in said reaction zone in proportions within the range of 1 to 10 volumes of propane per volume of cyclohexane such that the cyclohexane in the resulting mixture is substantially instantaneously brought to a temperature within the range of 1100 to 1500° F., maintaining the resulting mixture at a temperature within said range for a period of time within the range of 0.1 to 2 seconds to effect conversion of said cyclohexane to butadiene, cooling the resulting effluent of said zone, and separating butadiene therefrom.

25 6. A process for the production of butadiene from cyclohexane which comprises heating propane to a temperature above about 1300 but not above 1500° F. at a pressure in the range of about atmospheric to about 100 pounds per square inch gage, injecting a hydrocarbon fluid comprising 30 chiefly cyclohexane into said propane in proportions within the range of 1 to 10 volumes of propane per volume of said hydrocarbon fluid such that the cyclohexane in the resulting mixture is immediately brought within the range of from about 1300 to about 1500° F., holding the resulting mixture at a temperature within said range for a period of time within the range of 0.1 to 2 seconds to effect conversion of said cyclohexane to butadiene, cooling the resulting reaction products and separating butadiene therefrom.

35 7. A process for the production of butadiene from cyclohexane which comprises heating propane to a temperature above about 1300 but not above about 1500° F. effecting decomposition of 40 a portion of the propane; heating cyclohexane to an elevated temperature below that at which appreciable decomposition of the cyclohexane takes place, injecting the so heated cyclohexane into the mixture resulting from said heating of said propane in proportions within the range of one to ten gas volumes of propane for each gas volume of cyclohexane, the proportions being such that the temperature of the resulting mixture is substantially instantaneously brought 45 within the range of about 1300° F. to about 1500° F., maintaining the mixture at a temperature within said range for a period of time, between about 0.1 to about 2 seconds, sufficient to convert at least a portion of the cyclohexane to butadiene, cooling said mixture at the end of said period to a temperature below that at which substantial decomposition of cyclohexane takes place, and separating the butadiene from said mixture.

55 8. A process for the production of butadiene from cyclohexane which comprises passing a stream of propane through a closed elongated reaction zone of restricted cross-section at near-atmospheric pressure and at an elevated temperature such that the propane is heated to a 60 temperature above about 1300 but not above about 1500° F. effecting decomposition of at least part of the propane, injecting a hydrocarbon fluid comprising cyclohexane into the propane decomposition mixture, the proportions of propane and cyclohexane-containing fluid being within

the range of 1 to 10 volumes of propane per volume of cyclohexane such that the temperature of the resulting mixture is substantially instantaneously brought within the range of 1300 to 1500° F., the point of injection being so related to the outlet of said zone as to limit the residence time of cyclohexane at said temperature to a period of time within the range of 0.1 to 2 seconds, cooling the effluent of said zone to a temperature below that at which substantial decomposition of cyclohexane takes place, and separating the butadiene therefrom.

9. The process of producing butadiene from cyclohexane which comprises passing a stream of propane through a heated coil and thereby heating same to a temperature such that upon injection of cyclohexane thereinto in the manner hereinafter described the temperature of the resulting mixture is within the range of 1100 to 1500° F. whereupon cracking of said cyclohexane to butadiene will take place, injecting into said heated propane stream a relatively small volume of cyclohexane preheated to an elevated temperature somewhat below the cracking temperature and thereby substantially instantaneously heating said injected cyclohexane to the temperature at which it is cracked to butadiene, effecting said injection at a point in said coil located substantially ahead of the end of said coil and so located that said propane stream has attained said first-mentioned temperature and that the cyclohexane so injected will be held at the cracking temperature for a period of time

within the range of 0.1 to 2 seconds before reaching the end of said coil, flowing the resulting mixture through the remainder of said coil in said period of time which will effect optimum cracking of cyclohexane to butadiene, quickly cooling the effluent of said coil by admixture with coolant to a temperature below reaction temperature, and treating the cooled effluent to recover the butadiene content thereof.

10. The process of claim 9 wherein said cracking temperature is within the range of 1300 to 1500° F., wherein said cracking is conducted at a pressure ranging from about atmospheric to about 100 pounds per square inch gage, wherein said period of time is about 0.5 seconds, and wherein about 4 gas volumes of propane per gas volume of cyclohexane are employed.

11. The process of claim 9 including the further steps of recovering benzene from the effluent, hydrogenating said benzene to cyclohexane and employing the resulting cyclohexane together with fresh cyclohexane from an outside source as said cyclohexane injected into said heated propane stream.

12. The process of claim 9 further characterized by the fact that said propane is at least partially converted to butadiene simultaneously with cracking of cyclohexane during passage through said coil, and that the butadiene so formed is recovered together with the butadiene derived from cracking of said cyclohexane.

CHARLES E. AYRES.
